DESIGN.

—o—

J. NEIL.

CARPET.

No. 17,782.

Patented Oct. 11, 1887.

UNITED STATES PATENT OFFICE.

JOHN NEIL, OF BROOKLYN, NEW YORK, ASSIGNOR TO THE BIGELOW CARPET COMPANY, OF CLINTON, MASSACHUSETTS.

DESIGN FOR A CARPET.

SPECIFICATION forming part of Design No. 17,782, dated October 11, 1887.

Application filed September 8, 1887. Serial No. 249,193. Term of patent 3½ years.

To all whom it may concern:

Be it known that I, JOHN NEIL, of Brooklyn, county of Kings, and State of New York, have invented a new and original Design for 5 Carpets, of which the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

My design is composed of a body part, A, and a border, B.

The body is made up of indistinctly marked groups or masses of flower and leaf forms with occasional geometrical forms interspersed.

20 The larger masses contain at one end some prominent circular flowers with scalloped edges, surrounded by a body of small leaves with a few scroll forms among them. In the middle of the group or mass are several large 25 oval forms composed of radiating leaves surrounded with smaller ornamental work. A cluster of buds is supported at the top. At the other end of the group are several large geo-

metrical forms. The smaller groups are composed of a number of circular forms with leaves 30 radiating from one side and slender stems supporting buds above the points of the leaves.

The border B has an inner margin 35 ornamented with broad leaves inclosed within a conventional stem-work. Next to the margin 40 is a row of blocks or spaces ornamented with circular flowers with scalloped edges, or with pointed radiating leaves and other small leaf and flower forms. These blocks are surrounded with conical masses of ornamentation 45 having a double-scroll form at the base and two converging leaves or stems at the top. The rest of the border is covered with small ornamental figures.

What I claim as new, and desire to secure by 45 Letters Patent, is—

1. In a design for carpets, the body A, substantially as shown.

2. In a design for carpets, the border B, substantially as shown.

3. The design for carpets, consisting of the body A and border B, substantially as shown.

JOHN NEIL.
